UNITED STATES PATENT OFFICE.

LOUIS C. MILLS, OF LOS ANGELES, CALIFORNIA.

WICK-LIFTER FOR TORCHES.

1,053,629.

Specification of Letters Patent.

Patented Feb. 18, 1913.

Application filed July 16, 1912. Serial No. 709,817.

To all whom it may concern:

Be it known that I, LOUIS C. MILLS, a citizen of the United States of America, residing at Los Angeles, in the county of 5 Los Angeles, State of California, have invented a certain new and useful Wick-Lifter for Torches; and I do hereby declare the following to be a full, clear, and exact description of the invention, such as will enable others skilled in the art to which it 10 pertains to make and use the same.

This invention relates to a torch provided with a wick lifting device, and it may be said to consist in the provision of the 15 novel features and in the novel and improved construction, arrangement and combination of parts as will be apparent from the description and claim which follow hereinafter.

20 Objects of the invention are to provide a novel and improved device of the class specified which is simple in construction, economical to manufacture and use, strong and durable, convenient and easy to manipulate, and effective in action.

25 Other objects and the advantages of the invention will be apparent to those skilled in the art from a consideration of the following description of the preferred form of construction embodying the invention, taken in connection with the accompanying drawings in which—

30 Figure 1 is a partly broken and sectional side view of the device applied to a torch; Fig. 2 is a front view of one of the lifting members on the torch; Fig. 3 is a cross sectional view taken on the line 3—3 of Fig. 1, and Fig. 4 is a perspective view of parts of the lifting member in detached relation.

35 The tank 5 for containing oil or the like 6 may have screwed thereon a suitable hollow fitting 7 having thereon the preferably upwardly tapering spout 8 through which the preferably cylindrical wick 9 passes 40 from the interior of the tank 5. On the spout 8 are arranged one or more, preferably two, wick lifting members 4. The spout 8 may be formed with substantially oppositely disposed outwardly pressed portions 10 to 45 provide recesses 11 on the interior thereof. In the recesses 11 are movably fitted plates 12 having thereon lugs or guides 13 which extend outwardly through slots or guideways 14 in the outwardly pressed portions 50 10. The guides 13 may have thereon split

extensions 15 for connecting with the guides 13 suitable springs 16 and finger pieces 17. As shown, the springs 16 may be bow-shaped and arranged to have the end portions thereof bearing against the exterior of the spout 8 and they may be provided with substantially central openings 18 through which the extensions 15 may pass. The finger pieces 17 may be provided with openings 19 through which the extensions 15 may be 60 passed and the split portions 20 and 21 of the extensions 15 may then be bent into engagement with the finger pieces 17 to secure them and the springs 16 in position on the guides 13. One end portion 22 of the finger 70 pieces 17 may be suitably curved outwardly to facilitate manipulation of the device.

From the foregoing it will be understood that in use the wick 9 may be raised through the spout 8 by pressing inwardly with the 75 fingers on the lifting members 4 to move the plates 12 into clamping engagement with the wick 9 whereupon the plates 12 may be moved upwardly to lift the wick 9. When the lifting members 4 are released by the 80 fingers the springs 16 act to move the plates 12 back into the recesses 11 and the plates 12 may then be moved downwardly in the recesses 11 by pressing downwardly on the finger pieces 17.

85 While one form of construction in which the invention may be embodied has been particularly illustrated and described, there are many changes and modifications thereof that will readily occur to those skilled in the 90 art, wherefore, the right is reserved to all such changes and modifications as do not depart from the spirit and scope of the invention as defined in the appended claim.

95 I claim:

A torch provided with an upwardly tapering spout formed with substantially oppositely disposed outwardly pressed portions to provide recesses in the interior thereof, plates movably fitted in the recesses and 100 having thereon guides provided with split extensions and extending outwardly through guideways in the outwardly pressed portions, substantially bow-shaped springs arranged to have the end portions thereof bearing slidably against the exterior of the spout and provided with substantially central openings through which the extensions pass, finger pieces having one end portion thereof 105 curved outwardly and provided with open- 110

ings through which the extensions pass, the split portions of said extensions being bent into engagement with the finger pieces to secure them and the springs in position 5 on the guides, substantially as set forth.

In testimony whereof, I have signed my name to this specification in the presence of

two subscribing witnesses at Los Angeles, county of Los Angeles, State of California, this 9th day of July A. D. 1912.

LOUIS C. MILLS.
